UNITED STATES PATENT OFFICE.

SAMUEL WEBBER PARKER AND HENRY BLACKMAN, OF NEW YORK, N. Y.

FIRE-ESCAPE.

SPECIFICATION forming part of Letters Patent No. 289,701, dated December 4, 1883.

Application filed February 20, 1883. (No model.)

To all whom it may concern:

Be it known that we, SAMUEL W. PARKER and HENRY BLACKMAN, citizens of the United States, residing at New York, in the county 5 and State of New York, have invented new and useful Improvements in Fire-Escapes, of which the following is a specification.

This invention relates to certain improvements in fire-escapes; and it consists in certain 10 combinations, as will hereinafter more fully appear, and be pointed out in the claims.

The novel construction of our satchel is hereinafter set forth in detail, and illustrated in the accompanying drawings, in which—

15 Figure 1 is a front view, showing the satchel spread open. Fig. 2 is a cross-section in the line of the center of the satchel.

Similar letters indicate corresponding parts.

The letters A B designate the two parts or 20 sections of the satchel, hinged together on one of the longitudinal edges and provided with a suitable lock on the opposite edge, the letter o, Fig. 2, indicating the line of division between the sections. Both sections comprise a metallic frame, of any usual or suitable construction, 25 and with the section A is combined a supplemental frame, C, which is detachable therefrom, it being attached by set-screws s or other similar fastenings. This detachable frame carries 30 two arms or hangers, D, forming the bearings for a reel, E, on which is wound a rope, F, or a chain, which thence extends in a few coils around a friction-bar, G, and outward through suitable holes in the united frames to a handle, 35 H, its outer end being connected to the handle. The friction-bar G is fixed at the ends to the hangers D.

To the shaft of the reel E is fixed a brake-wheel, I, which is in peripheral contact with 40 one end of a brake-lever, J, the other end of which is pivoted to a rod, K, extending outward through the united frames, it being provided at the outer end with a handle, L, which is detachable. The brake-lever J is subjected 45 to the action of a spring, N, having a tendency to keep its free end in contact with the brake-wheel I, so that under normal conditions the reel E is thereby prevented from turning, while, if the rod K is pulled outward against the 50 spring the reel is released. The handle H of the satchel is attached, at or near its ends, to

the frame of the section A by means of two jaws, e, (best seen in Fig. 3,) which are pivoted to the frame, and one of which carries a hook, f, to engage a stud, i, on the other, so that when the jaws are opened the handle is set free, and hence is detachable; but other contrivances which will readily suggest themselves may be used for this purpose.

When the rope F is to be used as a fire-escape, 60 the handle H is detached and properly adjusted to the corner of a window or to any other suitable part of a room, to act as a brace for the rope. The satchel is then put out of the window and used as a seat or saddle by the person in 65 lowering himself to the ground, the rope being allowed to unwind from the reel in the descent as fast as may be desired, by properly adjusting the brake-lever J. As the rope thus unwinds, it is retarded by its contact with the 70 friction-bar G, so that in case the brake should get out of order the person may still descend with comfort; but the friction-bar is not essential to the apparatus.

For the purpose of adapting the handle H 75 to take a firm hold of the window or other support, it is curved backward at the ends and tapered to a point, as shown, so as to catch in the wood of the support.

Into each section A B of the satchel is fitted 80 a piece of cork or other suitable buoyant material, as at P, to form a float, which is held in place by straps m, Fig. 1, or other suitable fastenings, so that each section constitutes a life-preserver, and in order to allow the sections 85 to be applied to such use they are made separable from each other—namely, by means of their connecting-hinges, which are constructed as follows: On the proper edges of the sections are knuckles l, which are alternately secured to each section, and through which passes a removable pintle, g, the latter having at one end a head, g', and at the other end a nut, g'', or the like, for holding it in position.

To the sections A B, respectively, are connected end straps, Q, and side straps, Q', one set of each being provided with buckles or the like, so that when the sections are separated for use as life-preservers they can be secured 90 to the person in front and rear by means of 100 such straps, the end straps going over the

shoulders and the side straps around the body, below the arms. Said straps Q Q' may be either permanently or detachably connected to the sections, and in the example shown those of 5 the section B are permanent, while those of the section A are removable, they being provided with loops b, to engage with hooks or catches c. When the straps are not in use, they are placed into the satchel, so as to be readily accessible.

10 In the section A is a flap or partition, R, which is hinged on one edge, as at d, and arranged to close against a flange, R', Fig. 2, projecting inward from the proper frame, a packing-strip of india-rubber or other similar material being interposed between the flap and the flange to produce a water-tight joint. This flap R is held shut by means of hooks h, pivoted thereto, to catch into eyes h', which project from the flange R', through suitable holes in 15 the flap; but various other fastenings can also be used for this purpose. By said flap R the section A is provided with a compartment, S, Fig. 2, serving to receive various articles and to preserve the same against wet when the sections 20 are used as life-preservers, and to permit the flap to be thrown open to the full extent is the principal object of placing the reel E and its connections on a detachable frame, the latter being removed when the flap is to 25 be opened.

If desired, either section A B may be provided with a recess-opening on one end thereof, and having a suitable cover to receive a flask or other article; and one section, moreover, may have suitable attachments for supporting a hatchet, U, Fig. 1, or other similar instrument.

30 It may be remarked that our invention can

be applied to trunks as well as to satchels or bags.

What we claim as new, and desire to secure by Letters Patent, is—

1. The combination, with a satchel, of a detachable handle, a reel containing a rope or chain, the outer end of which is connected to 45 the handle, and a brake acting on the reel, substantially as described.

2. The combination, with a satchel, of a detachable handle having both ends curved and tapered, a reel containing a rope or chain, the 50 outer end of which is connected to the handle, and a brake acting on the reel, substantially as described.

3. The combination, with a satchel composed of two sections, of a reel mounted in bearings 55 within one section, a rope or chain wound on the reel, a brake-wheel, I, on the reel-shaft, a spring-impelled brake-lever, J, pivoted between its ends, and a handle-rod, K, having one end secured to the lever and its other end 60 projecting through the satchel, substantially as described.

4. The combination, with a satchel, of a reel containing a rope or chain, a friction-bar having the rope coiled on it, and a brake acting 65 on the reel, substantially as described.

In testimony whereof we have hereunto set our hands and seals in the presence of two subscribing witnesses.

SAMUEL WEBBER PARKER. [L. S.]
HENRY BLACKMAN. [L. S.]
